DESIGN FOR A CHIME

Milo F. Miller, Kansas City, Mo.

Application September 29, 1941, Serial No. 103,550

Term of patent 14 years

To all whom it may concern:

Be it known that I, Milo F. Miller, a citizen of the United States, residing at Kansas City, in the county of Jackson and State of Missouri, have invented a new, original, and ornamental Design for Chimes, of which the following is a specification, reference being had to the accompanying drawing, forming a part thereof.

Fig. 1 is a front elevational view of the chime, showing my new design.

Fig. 2 is a side elevational view thereof; and
Fig. 3 is a top plan view thereof.

I claim:

The ornamental design for a chime, as shown.

MILO F. MILLER.
